UNITED STATES PATENT OFFICE.

JOHN A. DOWD, OF FALL RIVER, MASSACHUSETTS.

BOILER STAYBOLT CONSTRUCTION.

1,399,942.

Specification of Letters Patent. Patented Dec. 13, 1921.

Application filed May 9, 1921. Serial No. 487,839.

To all whom it may concern:

Be it known that I, JOHN A. Dowd, a citizen of the United States, residing at Fall River, in the county of Bristol and 5 State of Massachusetts, have invented new and useful Improvements in Boiler Staybolt Constructions, of which the following is a specification.

This invention relates to boiler stay bolt 10 constructions, being more particularly designed where flexible connections are desirable in the fire box portion. The ends of the bolts on the fire side are normally exposed to the intense heat from the fire box 15 and as there is a considerable body of metal at that point these bolt ends are liable to be burned.

This invention provides a construction by 20 which the ends of the bolts are water jacketed, externally of the fire sheet, by water from the boiler, which not only effectually prevents burning of the parts, but adds to the effective heating surface of the boiler.

For a more complete understanding of 25 this invention, together with other objects and advantages thereof, reference may be had to the accompanying drawings illustrating an embodiment thereof, in which—

Figure 1 is a fragmentary cross section 30 through the fire box portion of the boiler at one of the stay bolts.

Fig. 2 is an elevation partly broken away 35 of a portion of the outside of the fire sheet with the bolt in position.

Fig. 3 is a similar view of the inside of the sheet.

Fig. 4 is a side elevation of the stay bolt.

Referring to Fig. 1, *a* and *b* represent the fire sheet and outside sheet respectively of the fire box portion of the boiler. These sheets are perforated at 1 and 2 in substantial alinement for the reception of the shank of a stay bolt 3, which may pass loosely therethrough.

As shown in Figs. 1 and 4 the head 4 of this stay bolt is made convex, the inner face thereof being adapted to be seated in a socket member 5 having a central hole in alinement with the hole 1 and positioned 50 on the outside of the fire sheet *a*. A nut 6, also convex, is seated in a similar manner in a socket plate 7 positioned on the outside of the sheet *b*. Adjacent the hole 1, sheet *a* is perforated at 8, there being mating

notches 9 in the socket 5. Caps 10 and 11 are positioned to house the bolt head 4 and the nut 6, the cap 10 extending externally of the perforations 8 and the notches 9. These caps are welded to the sheets *a* and *b* around their circumferences, as shown at 12. The formation of the bolt head and the nut allows the bolt a limited universal movement relative to the sheets *a* and *b* while retaining a proper seating engagement therewith. As the cap 10 extends outwardly of the perforations and notches 9, it is evident that water positioned between the sheets *a* and *b* in the boiler may circulate about and over the bolt head 4, thus forming a water jacket therefor. Furthermore, the cap 10 projects from the fire side of the sheet *a* where it is subjected to intense heat from the fire so that it adds to the effective water heating surface of the sheet.

Having thus described an embodiment of this invention, it is evident that various changes and modifications might be made therein without departing from its spirit or scope as defined by the appended claims:

1. A device of the class described comprising a pair of spaced boiler sheets having a pair of substantially oppositely positioned holes therein, sockets having holes therethrough in alinement with the holes in said sheets, a bolt passed loosely through said holes and having a rounded head seated in one socket, a nut having a rounded head seated in the other socket and threaded on the end of said bolt, and caps inclosing said bolt head and nut made fast to said sheets.

2. A device of the class described comprising a pair of spaced boiler sheets having a pair of substantially oppositely positioned holes therethrough, a socket positioned externally of each sheet and having a hole therethrough in alinement with the hole in the sheet, one of said sheets having perforations therethrough adjacent said hole, a bolt having a rounded head seated in one of said sockets, a nut threaded on the end of said bolt and having a rounded head seated in the other socket, and caps inclosing said head and nut and made fast to said sheets, one of said caps inclosing said perforations.

3. A boiler sheet having a hole therethrough for the reception of the shank of the stay bolt, perforations through said

sheet adjacent said hole, a stay bolt in said hole, and a cap inclosing the end of said stay bolt and said perforations and made fast to said sheet.

5. In combination, a boiler fire sheet, means on the fire side of said sheet for holding a stay bolt, a cap covering said means

and made fast to said sheet, and means whereby the inner face of said cap is in communication with water on the water side of 10 said sheet.

In testimony whereof I have affixed my signature.

JOHN A. DOWD.
